UNITED STATES PATENT OFFICE

THEODORE SCHISGALL, OF PARIS, FRANCE, ASSIGNOR, BY DIRECT AND MESNE ASSIGNMENTS, OF ONE-HALF TO MORRIS SALINGER AND ONE-HALF TO EMANUEL D. STEIN, BOTH OF NEW YORK, N. Y.

DESIGN FOR A DIAL FOR TIMEPIECES

Application filed December 31, 1930. Serial No. 38,168. Term of patent 7 years.

To all whom it may concern:

Be it known that I, THEODORE SCHISGALL, a citizen of the United States, residing at Paris, France, have invented a new, original, and ornamental Design in a Dial for Timepieces, of which the following is a specification, reference being had to the accompanying drawings, forming part thereof.

Figure 1, is a face view of a dial for time pieces showing my new design.

Figure 2, is an edge view.

I claim:

The ornamental design for a dial for time pieces as shown.

THEODORE SCHISGALL.
